AUTOMATIC CALENDAR

George Rollnick and Leo Friend, Los Angeles,
Calif.

Application February 12, 1934, Serial No. 710,832

8 Claims. (Cl. 40—117)

This invention relates broadly to time indicating devices and more particularly to an automatic calendar which presents for view at all times a calendar sheet for the current day.

5. A broad object of the invention is to provide an automatic calendar of the type indicated which is reliable in operation and is adapted to function over a relatively long period of time.

A full understanding of the construction and 10 operation of the invention may be had from the following detailed description which refers to the drawings.

In the drawings:

Fig. 1 is an elevational view of a calendar in 15 accordance with our invention, showing its external appearance;

Fig. 2 is a front elevation view of the machine with the case removed and the clock face and hands removed to reveal the mechanism;

20 Fig. 3 is a plan view of the mechanism with the case, clock face and clock hands removed;

Fig. 4 is a detailed sectional view of the calendar tape windup reel taken in the plane IV—IV of Fig. 3;

25 Fig. 5 is a detail end view of the ratchet mechanism on the takeup reel shown in Figs. 3 and 4;

Fig. 6 is a detail sectional view in the plane VI—VI of Fig. 3;

Fig. 7 is a detail view at right angles to the view 30 of Fig. 6 showing one of the cams for lifting the tape clamping bar;

Fig. 8 is another detail view of the cam in a different position of operation from that shown in Fig. 7;

35 Fig. 9 is a detail view partly in section taken in the plane IX—IX of Fig. 3, illustrating the trigger mechanism for releasing the folding contact of the machine; and

Fig. 10 is a schematic diagram showing the 40 electrical circuit of the device.

Referring first to Fig. 1, our assembled calendar comprises a case 1 of any desired ornamental shape having a window 2 through which a daily calendar is displayed and having a clock designated generally at 3. The calendar displayed

45 through the window 2 is printed on an elongated tape, this tape having a series of calendars printed thereon corresponding to successive days of the year. The mechanism which will next be described is for the purpose of supporting and moving this calendar tape every twenty-four hours to bring a new calendar into position behind the window 2.

Referring to Fig. 2, the calendar tape is initially wound on a feed spool or reel 4, which is

rotatably supported in a frame 5 back of and somewhat below the window 2 (Fig. 2). From the reel 4 the tape extends forwardly over a roller 6, thence upwardly back of the window 2, over a second guide roll 7 (Fig. 3), thence rearwardly 5 between a pair of feed bars 8 and 9 (Figs. 3 and 6), to a takeup reel 10 upon which it is wound.

It is essential that the calendar tape be moved exactly the distance between successive calendars thereon each twenty-four hours and furthermore 10 that the entire movement occur during a relatively short period of time at the end of each day (12 P. M.) To obtain this result, the feed bars 8 and 9 are reciprocated from their rear position,

as shown in Fig. 3, to a forward position spaced 15 therefrom the exact distance between successive calendars on the tape with the bars separated as shown in Fig. 6 so that the tape is not retracted.

Thereafter the bars are moved together to firmly grip the tape and are shifted rearwardly into the 20 position shown in Fig. 3, thereby moving the tape just far enough to expose the next calendar through the window 2 (Fig. 1). At the same time the takeup reel 10 is rotated to wind up the slack tape as the latter is fed by the bars 8 and 9. 25

Referring to Figs. 3 and 6, it will be observed that the lower bar 8 is slidably mounted upon a pair of rods 10 and 11, respectively, which guide the bar in its fore and aft movement. The rods 10 and 11 are firmly anchored at their outer 30 ends to the frame of the machine. The reciprocatory motion is applied to the bars by a crank pin 12 on a crank 13 mounted on a form wheel 14, which is adapted to be rotated by a worm 15, which in turn is driven through gears 16 and 17 35 from an electric motor 18 (Fig. 2). The worm wheel 14 has attached thereto on its under side a disc 19, the function of which will be described later, and both the worm wheel and disc are rotatably mounted on a stub shaft 20 journaled 40 in a frame member 21. The crank pin 12 is provided with a roller 22 which fits in a transverse slot in the under side of the bar 8, as shown in Fig. 6, the mechanism constituting a Scotch yoke.

45 As shown in Fig. 6, the upper tape clamping bar 9 is slidably supported for vertical movement to and from the lower bar 8 by guide pins 23 extending upwardly from the bar 8 through apertures provided therefor in the bar 9. The bar 9 50 is normally urged downwardly toward the bar 8 by spiral springs 25 surrounding the pins 23 and compressed between the upper face of the bar 9 and washers 27 on the heads of the pins. However, the upper bar 9 may be forced upwardly 55

away from the lower bar 8 against the pressure of the springs 25 to release the calendar tape 29, by cams 30 which are pivotally mounted by screws 32 to the lower bar 8. As shown in Fig. 7, when the cams are in vertical position they lift the bar 9. To move the cams into the bar-elevating position shown in Fig. 7 at the completion of each rearward stroke of the bars 8 and 9, pins 34 (Figs. 3, 7 and 8) are provided on the frame of the machine, and to release the cams into the position shown in Fig. 8 at the end of the forward stroke of the bars 8 and 9, similar pins 35 are provided on the frame of the machine. The pins 34 intersect the cams 30 just before the completion of the rearward stroke of the bar 8 to shift the cams into the position shown in Fig. 7, thereby elevating the bar 9 and releasing the tape 29. The pins 35 intersect the cams 30 just before completion of the forward stroke of the bar 8, thereby shifting the cams into the position shown in Fig. 8 and permitting the springs 25 to compress the upper bar 9 against the tape 29.

To rotate the tape windup reel 10, a rack 36 is secured to and extended rearwardly from the bar 8, which rack meshes with a pinion 37 keyed to a shaft 38 on which the reel 10 is journaled to rotate freely. Keyed to the opposite end of shaft 38 is a ratchet pawl 39 (Fig. 4) cooperating with a ratchet wheel 40 which is rigidly secured to a hub 41 rotatably mounted upon the shaft 38 and having attached thereto a friction disc 45 which bears against the end of the spool 10. A similarly directed ratchet wheel 46 is mounted alongside of a ratchet wheel 40, wheel 46 cooperating with a stop pawl 47. The takeup reel mechanism just described functions as follows:

During the rearward stroke of the bars 8 and 9, while the calendar tape is being fed by the bars, the rack 36 rotates the pinion 37 and shaft 38 in such a direction as to cause the pawl 39 to lock with the ratchet wheel 40 and rotate the hub 44 and disc 45 in such a direction as to rotate the spool 10 in a direction to wind up the slack tape, spool 10 being frictionally driven by the disc 45 which is pressed into engagement therewith by the spring 48. During the reverse movement of the feed bars 8 and 9, the rack 36 rotates the pinion 37 and shaft 38 in the opposite direction. This rotation, however, is not transmitted to the reel 10 for the reason that the pawl 39 slips over the teeth of the ratchet wheel 40 and the latter is positively prevented from moving with the pawl 39 by the stop pawl 47 cooperating with the ratchet wheel 46. It is necessary to provide a frictional drive between the hub 44 and the reel 10 for the reason that the reel 10 must turn through a different arc when empty than when full to wind up the same amount of tape. Hence, the pinion 37 is dimensioned to rotate the reel 10 sufficiently rapidly to take up all the slack when the reel is empty. Then as the reel fills up and it becomes unnecessary for it to rotate through as large an angle, slippage occurs between the driving disc 45 and the end of the reel.

It will be observed that the mechanism so far described functions to shift the calendar tape to bring a new calendar into view behind the window 2 in response to a complete rotation of the worm wheel 14. It is necessary, however, to provide some means for starting and stopping the motor 18 to cause it to drive the worm wheel 14 at the proper time and stop it at the completion of a revolution.

This control of the motor is effected by means of two pair of contacts connected in series in the energizing circuit of the motor, as shown in Fig. 10. Contacts 50 are mounted upon the clock 3 and are adapted to be closed by the clock at twenty-four hour intervals. The contacts 51 are under the joint control of the clock and the feed mechanism.

Referring to Fig. 2, it will be observed that the contacts 50 are so positioned on the clock that one of the contact members is intercepted by the crank pin 53 on a twenty-four hour wheel 54 of the clock. Thus wheel 54 is twice the size of, and is geared to, a gear 55 on the hour hand shaft of the clock. It is apparent that once during each twenty-four hours the pin 53 will close the contacts 50 and maintain them closed for an appreciable interval of time. In fact, it maintains the contacts 50 closed for such a long period of time that if the motor 18 were under the sole control of the contacts 50, the motor would wind up an entire year's calendar the first time the contacts 50 close. It is to prevent such an occurrence that the contacts 51 are provided.

Referring to Fig. 9, contacts 51 consist of a lower contact 51a resiliently supported from the frame of the machine and an upper contact 51b. Thus the contact 51a is mounted upon a shaft 56 which extends through an insulating bushing 57 the latter being anchored to the frame of the machine. A spring 58 surrounds the upper end of the shaft 56 and is compressed between the contact 51a and the end of the bushing 57. Electrical connection to the contact 51a is made at the lower end of shaft 56, as shown. The upper contact 51b is insulatingly supported on the end of a lever 59, which is fulcrumed to the frame of the machine by a pin 60. The opposite end of lever 59 extends above and over the disc 19 and is provided with a bearing pin 61 adapted to ride on the disc 19. Disc 19, however, is provided with an aperture 62, into which the pin 61 enters when the disc is in the position of rest shown in Fig. 3. A spring 63 is provided to constantly urge the lever 59 into the contact opening position shown in Fig. 9. To lock the lever 59 into contact closing position (in which the pin 61 is raised), a latch 64 is provided, this latch engaging the end of lever 59 when the latter has been moved into contact closing position. The latch 64 is pivotally supported on the frame in the space above the disc 19 so that the upper end of the latch is intercepted by the crank arm 13 when the latter rotates, to release the lever 59 and permit the pin 61 to drop against the disc 19.

The contacts 51 are closed and locked in closed position (by engagement of the latch 64 with the end of lever 59) once during each twenty-four hour interval, in advance of the closing of the contacts 50. The mechanism for closing the contacts 51 comprises a lever 65 (Fig. 2) which is fulcrumed on a pivot screw 66 secured to the frame of the device and has its right end extending over the contact end of lever 59 and its opposite end in the path of the crank pin 53 on gear 54. It will be readily apparent that as the gear 54 rotates in a counterclockwise direction the crank pin 53 will deflect the lever 65 to close the contacts 51 and will thereafter release the lever 65 before closing the contacts 50.

The device functions as follows:

With all the parts in the normal position shown in the drawings, continued rotation of the clock gear 54 first deflects the lever 65 to close the contacts 51 in the manner described, contacts 51 75

being held closed by engagement of the latch 64 with the end of lever 59. The continuing rotation of the gear 54 next closes the contacts 50, the device being preferably set so that this closure occurs at midnight. Closure of the contacts 50 completes the energizing circuit for the motor 18 and the latter thereupon rotates the crank 13 to reciprocate the feed bars 8 and 9. Since the previous movement of the bars 8 and 9 into their rear position of rest (the position shown in Fig. 3) moved the cams 30 into position to elevate the feed bar 9, as shown in Fig. 7, the calendar tape is released during forward movement of the bars 8 and 9. However, slightly before the bars 8 and 9 reach their extreme forward position, the cams 30 are engaged by the stop pins 35 and are shifted into the position shown in Fig. 8 in which the upper bar 9 is moved downward by the springs 25 to grip the tape. Therefore, during the reverse movement of the feed bars back into the position shown in Fig. 3 they carry the tape with them, thereby bringing a new calendar in front of the window 2 (Fig. 1).

The mechanism for stopping the motor at the completion of the reciprocation of the paper feeding carriage comprising bars 8 and 9 functions as follows:

Following the commencement of rotation of the crank 13, the latter intercepts the upper end of the latch 64 and deflects the latter to release the lever 59. The lever 59, however, drops only far enough to disengage the latch 64 and not far enough to open the contacts 51 because the disc 19 has then moved the aperture 62 out of registration with the pin 61 on lever 59 so that the pin rides on the surface of the disc and is prevented by the latter from moving into position to open the contacts 51. At the completion of the revolution of the disc 19 and crank 13, the aperture 62 is again brought into registration with the pin 61, permitting the latter to drop, thereby shifting the lever 59 into the position shown in Fig. 9 in which the contacts 51 are open. The opening of contacts 51, of course, stops the motor 18 and the latter will not be started again until the sequence of operations of the crank pin 53 on the top gear 54 is repeated twenty-four hours later.

To permit manual setting of the calendar tape, the shaft 38 which drives the windup spool 10 is preferably extended to the exterior of the case and a knob 70 mounted thereon, as shown in Fig. 1. By rotating this knob 70 the calendar may be advanced. To permit manual adjustment of the calendar in reverse direction, the shaft 11 (Fig. 2) on which the feed spool 4 is mounted, may also be extended to the exterior of the case and a knob 72 mounted thereon, as shown in Fig. 1.

Although for the purpose of disclosing the invention a specific embodiment thereof has been described in detail, it is to be understood that numerous modifications of the specific structure shown may be made without departing from the spirit of the invention and that the latter is to be limited only as set forth in the appended claims.

We claim:

1. In an automatic calendar, an elongated tape bearing spaced calendars each covering a predetermined interval of time, means defining a window for displaying one of said calendars at a time, means for moving said tape past said window comprising a feed spool, a windup spool, and a reciprocable carriage having gripping members for releasably engaging said tape, means associated with said carriage for actuating said grip-

ping members to grip said tape during movement of said carriage in one direction and move a new calendar to said window, means for releasing said gripping members and thereby prevent retraction of the calendar tape during reverse movement of said carriage, means for rotating said windup spool from movement of the carriage in said one direction to wind up said tape as it is shifted by said carriage, an electric motor and a mechanism driven thereby for reciprocating said carriage, a clock, and contact means associated with said clock and mechanism for energizing said motor to periodically reciprocate said carriage at the end of said predetermined interval.

2. An automatic calendar as described in claim 1 in which the means for rotating said windup spool comprises a rack connected to said carriage, a pinion meshing with said rack, and pawl and ratchet means for connecting said pinion in driving relation with said windup spool during feeding movement of said carriage.

3. An automatic calendar as described in claim 1 in which the means for rotating said windup spool comprising a rack connected to said carriage, a pinion meshing with said rack, a rotatable clutch member in frictional engagement with said windup spool, and pawl and ratchet means for rotatably connecting said pinion to said clutch member during feeding movement only of said carriage.

4. An automatic calendar as described in claim 1 in which said means associated with said carriage for actuating said gripping members comprises a rocker arm adapted to be rotated through an arc between two positions, in one of which said gripping means is actuated and in the other of which said gripping means is released, and stationary pin members positioned in the path of said rocker arm adjacent opposite ends of the stroke of the latter for shifting said rocker arm into one of its two positions at one end of the stroke and for shifting said rocker arm into the other of its two positions at the end of the opposite stroke.

5. An automatic calendar as described in claim 1 in which said contact means for energizing said motor includes a first pair and a second pair of normally open contacts connected in series with said motor, means actuated by said clock for periodically closing said first pair of contacts and maintaining them closed for a substantial interval of time, other means also actuated by said clock for periodically closing said second pair of contacts in advance of closure of said first pair of contacts, means for releasably locking said second pair of contacts in closed position following their closure by said clock actuated means, and means associated with said carriage reciprocating mechanism for releasing said locking means to open said second pair of contacts at the completion of each reciprocation of said carriage.

6. In an automatic calendar, an elongated tape bearing spaced calendars, each covering a predetermined interval of time, means defining a window for displaying one of said calendars at a time, means for moving said tape past said window comprising a feed spool, a windup spool and a tape shifting mechanism including a rotatable driving shaft, for successively shifting said tape the distance between successive calendars thereon in response to successive rotations of said driving shaft through a predetermined angle, means for rotating said windup spool in response to movement of said mechanism for winding up slack tape as the tape is moved by

said mechanism, an electric motor for rotating said driving shaft, a clock and contact means associated with said clock and said mechanism for periodically energizing said motor to drive said shaft and subsequently deenergize the motor in response to rotation of said shaft through said predetermined angle.

5 7. An automatic calendar as described in claim 6 in which said means for rotating said windup spool includes a friction clutch whereby said spool is yieldingly driven.

10 8. An automatic calendar as described in claim 6 in which said contact means for energizing said motor includes a first pair and a second pair of normally open contacts connected in series with said motor, means actuated by said clock for

periodically closing said first pair of contacts and maintaining them closed for a substantial interval of time, other means also actuated by said clock for periodically closing said second pair of contacts in advance of closure of said first pair of contacts, means for releasably locking said second pair of contacts in closed position following their closure by said clock actuated means, and means associated with said rotatable driving shaft for releasing said locking means to open 10 said second pair of contacts in response to rotation of said shaft through said predetermined angle.
